UNITED STATES PATENT OFFICE.

RALPH N. HILL, OF MONTCLAIR, NEW JERSEY, ASSIGNOR TO WESTERN ELECTRIC COMPANY, OF NEW YORK, N. Y., A CORPORATION OF ILLINOIS.

SELECTIVE SIGNALING SYSTEM.

1,103,288.

Specification of Letters Patent. Patented July 14, 1914.

Application filed March 21, 1912. Serial No. 665,244.

To all whom it may concern:

Be it known that I, RALPH N. HILL, citizen of the United States, residing at Montclair, in the county of Essex and State of New Jersey, have invented a certain new and useful Improvement in Selective Signaling Systems, of which the following is a full, clear, concise, and exact description.

This invention relates to an answer-back 10 for signaling systems, and more particularly to an answer-back for party line signaling systems wherein the different stations are selectively signaled.

The object of the invention is to provide 15 an answer-back system which shall be simple, inexpensive and reliable in operation.

In the signaling system to which this invention is applicable, there is provided a telephone set comprising a telephone transmitter in circuit with a local battery and the primary of an induction coil the secondary of which is adapted for connection with the line wires. The answer-back signal is obtained by causing rapid changes in the 25 resistance of the local circuit including the transmitter which will in turn induce a tone on the line to be heard at the call initiating station. The specific means provided for obtaining this signal consists of an electro- 30 magnetically operated vibrator mechanically associated with the telephone transmitter, and having a circuit including the local battery of the transmitter which is closed in the operation of the semaphore or other visual signal.

The drawing is a circuit showing the wiring of apparatus in a semaphore signaling system embodying this invention.

In the drawing 5 designates a despatcher's 40 or calling station and 6, 7 and 8 way stations all connected with line wires 10 and 11. Located at the despatcher's or calling station 5 is a central battery 12 adapted to be alternately connected and disconnected with the line wires 10 and 11 through contacts 13 and 14 on an impulse relay 15. The impulse relay 15 is in circuit with a local battery 16 and interrupting or transmitting key 17. Also connected with the line wires 10 45 and 11 at the despatcher's or calling station is a telephone set comprising a receiver 18 bridged across the line wires in series with a condenser 19 and the secondary of an induction coil 20, and a transmitter 21 in a

local circuit with a battery 22 and the primary of the induction coil 20.

The apparatus and circuits at each of the way stations 6, 7 and 8 are the same and as shown at station 6 and are as follows: Bridged across the line wires 10 and 11 is a selector mechanism comprising electromagnets 25 and 26 controlling the operation of a ratchet wheel 27 which closes contacts 29 to bridge an electromagnet 30 across the line wires 10 and 11. The electromagnet 30 when 65 energized withdraws a dog 31 from engagement with a vertically movable rod 32 connected with a semaphore arm 33 permitting said arm to move into its horizontal or danger position. The lower end of the movable 70 rod 32 is operatively connected with a clock train interrupting mechanism 39 which may be an ordinary district messenger call box and which when operated rotates a shaft 40 carrying contact wheels 35 and 36 to close 75 circuits through contact springs 37 and 38 as will hereinafter appear. Located at the way station is a telephone set comprising a receiver 45, a transmitter 46, induction coil 47, local battery 48, receiver switch hook 49 80 and condenser 50. In the talking and listening condition of the telephone set the transmitter 46 is in a local circuit closed through a contact 51 of the receiver switch hook 49 and including the local battery 48 and primary of the induction coil 47 in series therewith. The receiver circuit will be from line wire 10 over conductor 52, conductor 53, the receiver 45, secondary of induction coil 47, contacts 51 and 54 of the receiver switch 90 hook, conductor 55, conductor 56, condenser 50 and conductor 57 to the other line wire 11.

The means through which the answer-back signal is obtained are as follows: Mounted upon the back of the transmitter 46 95 is an electromagnetic vibrator 60 having an operating circuit including the local battery 48 and a normally closed contact 61 on the receiver switch hook. The operation of the vibrator 60 agitates the granular carbon or other comminuted material in the transmitter which causes a tone to be sent over the line through the same path as the outgoing voice currents which will be heard in the receiver at the despatcher's station.

Following now the operation of the answer-back mechanism and the various current paths thereof it will be assumed that

the receiver 45 is on the switch hook 49 and that the necessary number or character of current impulses have been sent to cause the closure of contacts 29. This of course will 5 cause the withdrawal of the dog 31 through the operation of the electromagnet 30 and operation of semaphore arm 33 and rod 32. As the rod 32 descends it causes the rotation of the shaft 40 and with it the interrupter 10 wheels 35 and 36. When contact is closed between wheel 35 and contact spring 37 an operating circuit is completed for the vibrator which may be traced as follows: from one side of battery 48, conductor 65, 15 conductor 66, winding of vibrator 60, conductor 69, contact 61, conductor 70, conductor 71, contact spring 37, wheel 35, shaft 40, a contact spring 72 bearing thereon and conductor 73 to the other side of battery 48. 20 Current in this path causes the operation of the vibrator which in turn sets up a variation in a circuit through the transmitter 46 also closed through wheel 35 and contact 37 and traced as follows: from one side of the 25 battery 48, conductor 65, transmitter 46, conductor 75, primary of induction coil 47, conductor 71, contact spring 37, wheel 35, shaft 40, spring 72 and conductor 73 to the other side of battery 48. The current in this 30 path is varied by the agitation of the granular carbon of the transmitter button caused by the operation of the vibrator 60 and induces a current on the line through the secondary of the induction coil 47. The path 35 for this current will be as follows: from one side of the secondary of induction coil 47 through the winding of the receiver 45, conductor 53, conductor 52, line conductor 10, receiver 18 at despatcher's station 5, line conductor 11, conductor 57, condenser 50, conductor 56, contact spring 38, interrupter wheel 36, shaft 40, wheel 35, contact spring 37, conductor 71 to the other side of the secondary of the induction coil 47. The make 40 and break of the wheel 36 and spring 38 interrupts the tone and thus produces a code answer-back.

It will be noted that the same battery is utilized for operating the vibrator 60 as is

used to supply current to the transmitter 56 thus avoiding the use of extra cells at the way stations with a consequent saving in installation and maintenance.

I claim:

1. In a signaling system the combination 55 with a pair of line wires, of a signal-transmitting station connected therewith, a signal-receiving station connected with said line wires, a telephone transmitter at said signal-receiving station adapted to be operatively associated with said line wires, vibrating means mechanically connected with said transmitter, and means at said transmitting station for receiving a signal resulting from the operation of said vibrating means. 65

2. In a signaling system the combination with a pair of line wires, of a signal-transmitting station connected therewith, a signal-receiving station connected therewith, a telephone transmitter at said signal-receiving 70 station adapted to be operatively associated with said line wires, an electromagnetic vibrator mechanically connected with said transmitter, and signal-receiving means at said transmitting station operatively connected with said line wires. 75

3. In a selective signaling system the combination with a pair of line wires having a transmitting station and a way station connected therewith, a selective signaling device 80 at said waystation, a telephone set at said waystation including a transmitter and a local battery adapted to be operatively associated with said line wires, an electromagnetic vibrator having a resonant connection 85 with said transmitter, a circuit for said electromagnetic vibrator including said local battery, circuit-closing means therefor controlled by said selector, and signal-receiving means at said transmitting station in circuit 90 to receive a signal resulting from the operation of said electromagnetic vibrator.

In witness whereof, I hereunto subscribe my name this 16th day of March A. D., 1912.

RALPH N. HILL.
